UNITED STATES PATENT OFFICE.

WILLIAM OWEN PAGE, OF TUCSON, ARIZONA.

VALVE-REMOVER.

1,319,415.

Specification of Letters Patent.

Patented Oct. 21, 1919.

Application filed January 13, 1919. Serial No. 270,960.

To all whom it may concern:

Be it known that I, WILLIAM O. PAGE, a citizen of the United States, residing at Tucson, in the county of Pima and State of 5 Arizona, have invented certain new and useful Improvements in Valve-Removers, of which the following is a specification.

This invention relates to wrenches, and more especially those which are inserted in 10 the object turned; and the purpose of the same is to produce a tool for insertion into the valve insides of a Schrader tube nipple for removing the same when desired.

With this object in view, the invention 15 consists in a javelin of peculiar external configuration, channeled along one side for a purpose yet to appear.

In the drawings—

Figure 1 is a sectional view through a 20 complete Schrader valve, showing the tool in use

Fig. 2 is a perspective view of the tool or wrench on an enlarged scale.

The construction of the Schrader valve is 25 well known. In the drawings the letter N designates the nipple and I the valve insides as a whole. We are concerned only with the threads 1 at the outer end of the nipple, the tubular plug 2 which screws into them when 30 the insides of the valve are inserted, and the rod which extends loosely through this plug and is flattened as at 3. My improved tool, best seen in Fig. 2 is a javelin made of a stout piece of wire having a straight round

35 body indicated at 4, a handle 5 at its outer or upper end, which handle may take any appropriate form but is herein shown as a right-angular bend, and a pointed or reduced lower end 6. This end is channeled along 40 one side as at 7 for more than half the thickness of the body 4, the channel running out at an appropriate point 8, but the other or outer side of the end 6 follows the contour of the body. The channel may be cut on 45 an angle or a curve, and if the latter, then the cross section of the pointed end of the tool or implement would be of crescent shape.

In the use of this device, the tool is inserted into the outer end of the nipple N

as seen in Fig. 1, its channel receiving the 50 wire and being of appropriate depth to receive the flattened portion 3 thereof. The rounded side of its pointed end 6 faces outward if we assume that the wire stands along the center of the bore through the tubular 55 plug 2, and the extreme point of the tool passes into said bore and is pushed down into the same until it reaches the position shown in Fig. 1 or when it wedges in place therein and firmly grips the plug without having 60 deflected the wire to an undue extent. Now by rotating the tool by means of its handle, a plug may be turned within the threads 1 and withdrawn from the mouth of the 65 nipple, and therefore, the entire valve insides 70 can be readily removed. I find this tool more useful than the ordinary implement employed for withdrawing the insides, and its utility is probably due to the fact that in pushing the point of the tool into place, 75 the wire is to a slight extent deflected from its axial position, with the result that the valve on the wire is pressed away from or out of adhesive contact with its seat; and thereafter, the rotary movement of the body 75 4 of the tool which turns the plug is not resisted by the sticking of the valve, and in fact, the movement of the tool turns the wire and probably the valve itself. In any event, I have been able to remove the insides with 80 this tool where they could not be removed with anything else.

The foregoing description and the drawings have reference to what may be considered the preferred, or approved form of my 85 invention. It is to be understood that I may make such changes in construction and arrangement and combination of parts, materials, dimensions, et cetera, as may prove expedient and fall within the scope 90 of the appended claim.

Having thus fully described my invention, what I claim as new and desire to secure by Letters Patent is:—

As a new article of manufacture, a valve 95 remover formed from a strand of comparatively heavy cylindrical material forming a body, said body being bent contiguous to

one end to form an angularly extending handle, said body being tapered adjacent its opposite end to a point, said body being longitudinally channeled from adjacent said 5 point, the inner end of said channel terminating in a point contiguous to the center of said body, for the purposes set forth.

In testimony whereof I affix my signature in presence of two witnesses.

WILLIAM OWEN PAGE.
